UNITED STATES PATENT OFFICE.

EUGENE J. LOGAN, OF BALTIMORE, MARYLAND, ASSIGNOR TO THOMAS D. MILLER, OF BALTIMORE, MARYLAND.

MACHINE FOR CUTTING TUBULAR BODIES.

No. 823,422.

Specification of Letters Patent.

Patented June 12, 1906.

Application filed November 18, 1903. Serial No. 181,655.

To all whom it may concern:

Be it known that I, EUGENE J. LOGAN, a citizen of the United States, residing at Baltimore, in the State of Maryland, have invented certain new and useful Improvements in Machines for Cutting Tubular Bodies, of which the following is a specification.

The purpose of my invention is to provide a machine for cutting off the ends of tubular bodies, and the machine made according to my invention is designed particularly for the purpose of cutting off the ends of tin cans such as are largely employed for containing and preserving foodstuffs. At present when the contents of these cans have been removed by cutting open their heads the cans are thrown away as worthless. With my machine I am enabled to cut off the ends or heads of these cans very rapidly, so that the body portions may be preserved, and after being cut open longitudinally and flattened these body portions are converted into flat rectangular pieces of sheet metal, for which there is a large demand in the manufacture of small articles. By means of my invention a very large amount of material which now goes to waste may be saved. While the invention is particularly adapted for this purpose, it may be used for trimming or cutting off the ends of tubular bodies of any description.

In the accompanying drawings, Figure 1 is a front elevation of the machine, one-half of the saw-gear being shown in central section. Fig. 1^a is a detail view showing one of the clutch-pins connected with the saw-carrier. Fig. 2 is an end view looking from the left of Fig. 1. Fig. 2^a is a detail view showing the movement of the saws relatively to a holder. Fig. 3 is a top plan view of the machine. Fig. 4 is a front view of the can-cleaning mechanism. Fig. 5 is a side view of the ratchet mechanism for operating the feed-wheel looking from the left in Fig. 1, the pawl being shown at the limit of its upward movement with the locking-pin which locks the feed-wheel lifted by the cam-surface of the pawl. Fig. 6 is a view of the same parts looking from the right in Fig. 1, but showing the pawl started on its downward movement and the locking-pin resting upon the curved surface of the detent-wheel. Fig. 7 is a central vertical section through the worm-wheel and clutch mechanism by which the machine

is connected to the driving power, and Fig. 8 is a section on the line 8-8 of Fig. 7.

Referring to the drawings, A indicates the supporting-frame of the machine, at the rear end of which is mounted a driving-shaft 1, carrying fast and loose pulleys 2 and 3, to which the ordinary shifting-belt from any suitable source of power is in practice applied for the purpose of operating the machine.

Upon a shaft 4, arranged parallel with the driving-shaft and at about the longitudinal center of the supporting-frame, is a feed-wheel 7, carrying on its periphery a series of clamps or holders 8, each adapted to hold an ordinary tin can firmly when the movable jaw 8^a of the clamp is pressed toward the fixed jaw 8^b. For the purpose of gripping the can-body firmly without excessive pressure the semicircular faces of these jaws are preferably lined with rubber or some other suitable material which will prevent the can from turning in the clamp. This feed-wheel extends upward through a slot 9 in the top or bed 10 of the supporting-table and carries the clamps between a pair of circular saws 11, which operate in the manner hereinafter described to sever the ends of the cans from their body portions. The clamps are not quite equal in width to the length of the cans C, so that the ends of the cans project at each side of the clamps just far enough to permit the saws to come between the ends of the can-bodies and the ends of the clamps. The saws are arranged so that they will run as closely as possible to the ends of the clamps in order to take advantage of the shearing action between the saws and the adjacent ends of the clamps, as will be hereinafter referred to.

The feed-wheel 7 is operated intermittently by means of a ratchet-wheel 12, secured to the shaft 4, (see Figs. 2, 5, and 6,) and a pawl 13, engaging said ratchet-wheel and operated by means of a cam 14 upon a shaft 15, which is arranged transversely of the machine. The pawl 13 is secured to an arm 13^a, journaled upon the shaft 4, and the outer end of said arm is connected by a link 13^b to a strap 13^c, encircling the cam 14. This shaft 15 is geared to a shaft 16, similarly located and arranged at the opposite side of the feed-wheel by means of sprocket-wheels 17 and 18 of equal diameter, secured to said

shafts respectively and connected by a sprocket-chain 19. These shafts are revolved in unison by means of a worm-wheel 20, secured to the shaft 16 and engaged by a worm 21 upon the main shaft 1. The pawl 13 makes one downward and one upward movement for each revolution of the shaft 15. In the drawings eight clamps are shown connected to the periphery of the feed-wheel, and the movement of the pawl is so proportioned that at each downward movement it will rotate the feed-wheel one-eighth of a revolution, and thus bring the clamps in succession to the saws at the top of the machine. During the upward movement of the pawl the feed-wheel remains stationary with one of its clamps in position for the saws to operate upon the can held within the clamp. If a smaller or greater number of clamps are used, of course the travel of the feed-wheel at each movement of the pawl will be varied accordingly by varying the travel of the pawl.

In order to lock the feed-wheel against movement while the heads of a can are being cut off, a detent-wheel 22, Figs. 1 and 6, is arranged upon the shaft 4, and this detent-wheel is provided with eight equidistant slots 23 in its periphery, which are engaged successively by a spring locking-pin 24, mounted upon a fixed part of the frame. This locking-pin is held out of engagement with the detent-wheel during the downward movement of the pawl and engages one of the slots in said wheel after the pawl has completed its downward movement and during the upward movement of the pawl. This is accomplished by means of a cam-surface 25 upon the pawl, which engages a projection 26 upon the locking-pin and lifts the latter out of engagement with the detent-wheel just before the pawl reaches the limit of its upward movement. This cam-surface holds the locking-pin in its disengaged position until the pawl again starts downward, and as the downward movement of the pawl causes the detent-wheel to turn with the ratchet-wheel and feed-wheels, the slot which the locking-pin had just been lifted out of will move downward out of alignment with the pin before the latter is released from the cam-surface 25. As soon as the pin is released it drops upon one of the arcs 27 of the periphery of the detent-wheel between adjacent slots 23, as shown in Fig. 6, and rides upon this arc until the pawl completes its downward movement, when the pin drops into the next slot which is brought into alignment with the pin, and the feed-wheel shaft therefore becomes locked in position until the pawl again approaches the limit of its upward movement.

The saws are given a rapid continuous circular movement and an intermittent orbital movement concentric with the axis of the adjacent clamp in order to sever the heads from the cans. Both saws are similarly mounted

and operated by similar trains of gearing mounted upon supports on the bed of the machine, the two saws and their gearing being arranged at opposite sides of the feed-wheel. A description of one set of gearing will therefore apply to both. As shown in Fig. 1 of the drawings, each saw is secured to an arbor or saw-shaft 28, journaled in a head 29, forming part of a rotatable saw-carrier B, said saw-carrier comprising a sleeve 30, journaled in a bearing 31, which is carried by a standard 32, mounted upon the bed of the machine, and collars 33 and 34, secured to said sleeve at the ends of the bearing. This sleeve is rotated intermittently, as will be hereinafter described, to give the saw its orbital movement. A shaft 35 extends longitudinally through the sleeve and is journaled therein and also within a bearing in a standard 36 at the end of the machine-frame. This shaft 35 is geared to the saw-shaft 28 by means of a gear 37 upon the shaft 35 and a pinion 38 upon the saw-shaft, this gear and pinion being arranged within a recess 39 in the head 29. The shaft 35 is driven by means of a gear 40 upon said shaft, meshing with a gear 41 upon a counter-shaft 42, which is journaled in standards 36 and 43 upon the bed of the machine and driven by a sprocket-chain 44, passing around a sprocket-wheel 45 upon the shaft 42 and a sprocket-wheel 46 upon the main shaft 1. This arrangement of gearing gives each saw a rapid circular movement, and as the feed-wheel carries a can to the saws the latter cut into the can-body at the rear and near the top of the can, as indicated in Fig. 2^a. The normal positions of the saws are shown in Fig. 1, and their direction of rotation is indicated by an arrow *a* in Fig. 2^a. As soon as a can is brought into position and the feed-wheel locked against movement by the locking-pin 24 the saws commence their orbital movement in the direction indicated by the arrow *b* in Figs. 2 and 2^a. As the saws travel around the can-body it will be seen that the teeth of each saw will cut circumferentially around the can-body from the interior outwardly, and as there is very little clearance-space between the saws and the adjacent ends of the clamp advantage is taken of the shearing action between the saws and the edges of the clamps. By reason of this the cutting work of the saws is more effective than if the saws revolved in the opposite direction, in which case the teeth would cut from the outer surface of the can inward. This orbital movement of each saw is accomplished by the rotation of the saw-carrier B, by which it is carried and which is automatically started when a can is brought into position for cutting and which is automatically stopped after the saw-carrier has made a complete revolution, so that the saws will be held in proper position to engage the succeeding can. In order to intermittently op-

- erate the saw-carrier, a gear 47 is loosely journaled upon one end of the sleeve which is extended beyond the collar 34 and is engaged by a pinion 48 upon the constantly-driven counter-shaft 42. The collar 34 is secured to the sleeve 31, and this collar, which forms a clutch-head for connecting the saw-carrier to the loose gear 47, is provided with a spring-pin 49, adapted to engage a socket 49^a in the adjacent face of the loose gear 47. The collar or clutch-head 34 has a peripheral groove 49^b, and the pin 49, Fig. 1^a, extends transversely across this groove and has in its side a recess 50, forming a shoulder 51, which when the pin is in engagement with the gear is at one side of the center of the peripheral groove. This pin is normally disengaged from the socket in the gear-wheel by a shoe or cam 52, having a beveled forward end 53. (See Fig. 3.) This cam is mounted upon a lever 54, which is intermittently moved to raise and lower the cam within the groove. When the lever 54 is raised, the spring-pin is released and engages one of the notches in the gear-wheel 47 and the saw-carrier makes one revolution, the saw passing around the can-body which is held stationary in the clamp and severing the head. After the carrier has made one revolution the pin in the clutch-head is withdrawn from engagement with the loose gear 47 by the engagement of the cam-surface 53 with the shoulder 51, the cam having been lowered into the bottom of the groove 49^b during the revolution of the saw-carrier for that purpose. To insure the stoppage of the saw-carrier at the same point after each revolution and to lock it in this position, a locking-lever 55 is raised and lowered simultaneously with the movement of the cam-lever 54, and this locking-lever carries a pin 56, which engages a notch 57 in the collar 33, which is secured to the sleeve 30 as soon as the locking-pin in the clutch-head is withdrawn from the loose gear. The sleeve is therefore prevented from turning until both the cam-lever 54 and locking-lever 55 are raised.
- As shown, the levers 54 and 55 are each similarly mounted upon pivot-pins 59 in brackets 60, extending upwardly from the sleeve-bearing 31, and the adjacent ends of said levers overlap and each is provided with a slot 61, these slots registering with one another. A spring 62, arranged between the adjacent ends of the levers and the top of the bearing 31, presses upwardly upon said adjacent ends and forces the cam on the lever 54 and the locking-pin on the lever 55 downwardly against their engaging parts.
- As soon as a can is brought to the saws by the feed-wheel and the latter has become locked by the spring-pin 24 the levers 54 and 55 are raised to release the sleeve 30 and connected with the loose gear by means of a rod 63, having at its upper end a pin 64, which extends through the slots 62 in said levers, and at its lower end a pin 65, which is engaged by a cam 66 upon one of the shafts 15 or 16, as the case may be. This rod has a longitudinal slot 67 in its lower end, through which the shaft extends, and this slot is of sufficient length to permit the required movement of the rod. As soon as a can-body is brought to the saws and the feed-wheel locked the rod 63 is moved downward by the engagement of the cam 66 with the pin 65 and the sleeve carrying the saw is clutched for a short space of time to the loose gear 47 and the saw makes its orbital movement while the feed-wheel is stationary and the pawl which operates the feed-wheel is making its return movement. As soon as the cam 66 has passed the pin 65 the spring 62 forces the outer ends of the levers 54 and 55 downward and raises the rod 63. The cam 52 upon the lever 54 then rides in the bottom of the groove 49^b and the spring locking-pin 56 rides upon the periphery of the collar 33 until the sleeve has completed its revolution, when the clutch-pin 49 is withdrawn by the cam 52 and the spring locking-pin 56 drops into the depression 57 in the collar 33 and locks the sleeve until another can is brought into position and the rod 63 again tripped by the cam 66 acting upon the pin 65.
- As the feed-wheel shown in the drawings carries eight can-clamping devices, it is moved through one-eighth of a revolution at each operation of the moving pawl 13, which is operated by the cam 14 upon the shaft 15. As the shafts 15 and 16 rotate in unison, the sleeves carrying the saw mechanism are operatively connected with the loose gears 47 simultaneously eight times during the revolution of the feed-wheel by the engagement of the cams 66 upon the shafts 15 and 16 with the pins 65 upon the rods 63.
- The operator stands at the front of the machine and as each clamp rises above the bed of the machine a can is inserted within it, the ends of the can projecting beyond the ends of the clamp. Each clamp has upon its loose jaw 8^a a roller 70, which just before the clamp reaches its vertical position engages the inner or lower face of an arcuate guide 71, arranged concentric with the feed-wheel shaft 4. This guide bears upon the rollers 70 of the clamps or holders and presses the loose jaws firmly around the cans. The forward end 71^a of this guide is inclined or turned slightly upward so as to afford a cam-surface which will properly engage the rollers and press the loose jaws of the holders upon the can-bodies. The guide 71, as shown, is nearly semicircular, so that after the heads of the cans have been removed by the saws the cans will be securely held within the holders until they reach the lower part of the machine, when the rollers will pass beyond the lower end 71^b of the guide. When the roller 70

of a holder passes from the lower end of the guide, the hinged jaw of the holder drops away from the can by gravity and the can falls out onto the floor or receptacle or any suitable conveyer for removing the headless cans.

As the cans which have contained food-stuffs generally have some remnants of their former contents adhering to their inner walls, I provide means for cleaning the interiors of the cans during the intervals occurring while the feed-wheel is stopped and the saws are making their orbital movement. For this purpose I provide a brush 72, Fig. 4, which is mounted upon a spindle 73, Figs. 2, 3, and 4, the latter being journaled in a cross-head 74, movable in a guideway 75. Spindle 73 is arranged at right angles to the plane of the feed-wheel and in such position that it will when moved longitudinally pass diametrically into the interior of each holder in succession as the latter carrying the headless cans come to a position of rest opposite the brush. This cleaning operation takes place while the holders are closed firmly upon the cans by the pressure of the curved guide 71. The brush-spindle 73 is rapidly rotated by means of a belt driven from any suitable power and applied to a wide flange-pulley 76 upon the spindle. The brush-spindle is given a quick reciprocating movement by means of a cam 77, mounted upon the shaft 15, which cam engages a roller 78 upon a lever 79, pivoted at its lower end to a suitable support 80 and having at its upper end above the cam a vertical slot 81, which is engaged by a pin 82, secured in a fork 73^a, attached to the cross-head 74. The brush-spindle is normally drawn in the direction of the feed-wheel by a spring 83, connected to the upper end of the lever 79 and to a fixed part of the machine. The greater portion of the periphery of the cam-wheel 77 is concentric with the shaft 15, to which it is secured. At one part of its periphery the cam has a rather abrupt depression 77^a, which permits the lever 79 to be drawn over toward the feed-wheel by the spring 83 for a distance of four or five inches, so that the brush, which is rapidly rotated, may enter and clean the interior of a headless can. The cam then forces the roller 78 out of the depression 77^a and the brush is withdrawn from the interior of the can-body, so as not to interfere with the succeeding movement of the feed-wheel. As the cam 77 is mounted upon the shaft 15, a reciprocating movement will be given to the brush eight times during each revolution of the feed-wheel, and the depression 77^a in the cam 77 is so located as to give this back-and-forth movement of the brush-spindle during the intervals while the feed-wheel is stationary. While the roller 78 is riding upon the concentric or circular portion of the cam 77 the

brush-spindle will of course have no longitudinal movement.

In the drawings the parts are shown in the position where the heads of a can-body have just been cut off and the feed-wheel is about to be moved by the feed-pawl 13. The sleeves carrying the saws are locked in their normal position. The saws, as has been stated, are constantly driven at a high rate of speed. The next operation which takes place is the movement of the feed-wheel through one-eighth of a revolution by the downward movement of the feed-pawl. This brings a new can-body to the saws, and the latter make incisions in the can-body before the feed-wheel comes to a complete stop. As soon as the feed-wheel is stopped it is locked against further movement, and the sleeves carrying the saws are connected to the constantly-driven gears 47 by the depression of the rods 63, which are tripped by the cams 66. These rods release the locking and clutch levers at their upper ends, and the springs 62, bearing against these levers, again set them into position for stopping the sleeves after the saws have rotated about the can-body. While this orbital movement of the saws is taking place and the feed-wheel is locked the roller upon the lever 79 enters and leaves the depression in the cam 77, and a headless can is cleaned by the rotating brush upon the spindle connected with the lever 79. These operations take place during the upward movement of the feed-pawl 13 and are completed before the pawl unlocks the feed-wheel and starts on its downward movement. The headless cans drop from the holders when the latter reach the bottom of the curved guide.

The machine is automatic in its action throughout, and with an expert operator who can place the cans in the holders as fast as the feed-wheel is operated it is unnecessary to stop the machine. I provide means, however, whereby a less expert operator may start the machine after a can is placed in a holder and automatic means for stopping the machine after the feed-wheel has moved forward one step and said can has been operated upon by the saws. For this purpose the worm-wheel 20 is mounted loosely on the shaft 16 and a wheel 85, Figs. 2, 3, 7, and 8, is secured to said shaft adjacent to the worm-wheel, and these wheels, which serve as the opposing members of a clutch, are normally connected, so as to cause the rotation of the shaft by a spring-pin 86, arranged transversely of the wheel or member 85 and engaging a notch in the worm-wheel. The member 85 has a peripheral groove 87, and the pin which extends across the groove has a slot 88 cut in its side, forming a shoulder 89, which is engaged at the completion of each revolution of the wheel by a shoe 90, having a bevel

eled forward end 91 and fitting within the groove 87. This shoe, as shown, is secured to an arm 92, which is journaled upon a stud 93, fastened to a part 94 of the frame of the machine. The arm 92 is connected by a link 95 to a treadle 96, and the latter is pivoted at its rear end to a fixture 97 upon the floor. The treadle is supported normally by a spring 98, so that the shoe 90 is held within the groove in the wheel 85. When the shoe is thus held within the groove, it will be evident that the clutch-pin will be disengaged at the completion of each revolution and that the machine will stop until the shoe is moved out of the groove by the depression of the treadle. An operator who is not expert, therefore, after placing a can within a holder depresses and immediately releases the treadle, and the machine goes through one series of operations and then comes to a stop automatically. When an expert operator is handling the machine, the treadle is kept permanently depressed by the foot or any suitable means and the machine runs constantly.

The complete operation of the machine will be readily understood from the foregoing without further description.

While the ordinary toothed circular saws are found most suitable for use in connection with my machine, any other circular sawing devices suitable for the purpose, either with or without teeth, may be used, and I do not wish to confine my claims to any particular kind of circular saw.

Having described my invention, what I claim, and desire to secure by Letters Patent, is—

1. The combination with a holder for tubular bodies, of a circular saw adjacent to an end of said holder, means for rotating said saw about its axis, and means for giving said saw an orbital movement about the axis of the holder.

2. The combination with a holder for tubular bodies, of a circular saw adjacent to an end of said holder, means for rotating said saw about its axis, and means for giving said saw an orbital movement about the axis of the holder intermittently.

3. The combination with a holder for tubular bodies, of a pair of circular saws arranged adjacent to the ends of said holder, means for rotating said saws about their axes, and means for giving said saws an orbital movement about the axis of the holder.

4. The combination with a holder for tubular bodies, of a pair of circular saws arranged adjacent to the ends of said holder, means for rotating said saws about their axes, and means for giving said saws an orbital movement about the axis of the holder simultaneously.

5. The combination with a holder for tubular bodies, of a pair of circular saws arranged

adjacent to the ends of said holder, means for rotating said saws about their axes, and means for giving said saws an orbital movement about the axis of the holder simultaneously and intermittently.

6. The combination with a circular saw, and means for rotating the same about its axis, of a feeding device having one or more holders for tubular bodies thereon, means for moving said feeding device intermittently to bring the tubular bodies against the saw, and means for giving said saw an orbital movement about the axis of each tubular body after it has been brought into engagement with the saw.

7. The combination of a saw-carrier journaled in a suitable bearing and a saw-arbor journaled in said carrier at one side of the axis of the carrier, a saw mounted upon said arbor, a shaft extending axially through said saw-carrier and geared to said arbor, means for rotating said shaft, and means for intermittently rotating said saw-carrier.

8. The combination of a saw-carrier journaled in a suitable bearing and a saw-arbor journaled in said carrier at one side of the axis of the carrier, a saw mounted upon said arbor, a shaft extending axially through said saw-carrier and geared to said arbor, means for rotating said shaft, means for rotating said saw-carrier, and means for locking the saw-carrier against movement at the completion of each revolution of the carrier.

9. The combination of a saw-carrier journaled in a suitable bearing and a saw-arbor journaled in said carrier at one side of the axis of the carrier, a saw mounted upon said arbor, a shaft extending axially through said saw-carrier and geared to said arbor, means for rotating said shaft, means for rotating said saw-carrier, intermittently, comprising a constantly-driven clutch member, a co-operating clutch member secured to the carrier, means for automatically connecting said clutch members, and means for automatically disengaging said clutch members at the completion of each revolution of the carrier.

10. The combination of a saw-carrier journaled in a suitable bearing and a saw-arbor journaled in said carrier at one side of the axis of the carrier, a saw mounted upon said arbor, a shaft extending axially through said saw-carrier and geared to said arbor, means for rotating said shaft, means for rotating said saw-carrier, intermittently, comprising a constantly-driven clutch member, a co-operating clutch member secured to the carrier, means for automatically connecting said clutch members, means for automatically disengaging said clutch members at the completion of each revolution of the carrier, and means for automatically locking the carrier against movement while the clutch members are disengaged.

11. In a machine for cutting tubular bodies,

- the combination with a suitable bearing and a saw-carrier comprising a sleeve journaled in said bearing, and having a head adapted to support a saw-arbor at one end of the bearing and a clutch member fixed to said sleeve at the opposite end of the bearing, of a constantly-driven clutch member journaled upon said sleeve, means for automatically engaging and disengaging said clutch members, a shaft extending axially through said sleeve, means for constantly driving said shaft, a saw-arbor mounted in said head parallel with the shaft and having a saw thereon, and gearing connecting said shaft and arbor.
12. In a machine for cutting tubular bodies, the combination with a suitable bearing and a saw-carrier comprising a sleeve journaled in said bearing, and having a head at one end adapted to support a saw-arbor and a clutch member secured to said sleeve at the opposite end of the bearing, of a gear, forming a clutch member, journaled upon said sleeve, a saw-arbor journaled in said head, a shaft extending axially through said sleeve and geared to said saw-shaft, a counter-shaft, and gearing connecting said counter-shaft with the shaft extending through the sleeve and with the gear journaled upon said sleeve.
13. In a machine for sawing tubular bodies, the combination with a saw-carrier comprising a sleeve journaled in a suitable bearing, of a clutch upon said sleeve at one end of said bearing, a collar secured to said sleeve at the opposite end of the bearing, a clutch-lever and a locking-lever pivoted adjacent to said bearing, said clutch-lever being adapted to engage and operate the clutch and said locking-lever being adapted to form a locking engagement with the collar, a rod connected to the free ends of said levers, and a shaft having a cam thereon adapted to operate said rod.
14. In a machine for sawing tubular bodies, a rotatable saw-carrier, a saw carried thereby at one side of the axis of the carrier, means for rotating said saw, means for intermittently rotating said carrier, a feed-wheel having one or more holders, each adapted to hold a tubular body with its end projecting in the plane of the saw, means for operating said feed-wheel to bring the tubular body or bodies into engagement with the saw, and means for holding said feed-wheel stationary while the saw-carrier is in motion.
15. In a machine for sawing tubular bodies, a rotatable saw-carrier and means for rotating the same, a saw-arbor journaled in said carrier at one side of the axis of the carrier, said arbor having a saw thereon, a feeding device having one or more holders thereon each adapted to hold a tubular body, means for constantly rotating said saw, means for holding said carrier stationary, means for moving said feeding device to bring a holder opposite the end of the saw-carrier, with the tubular body in engagement with the saw, means for automatically starting said carrier into operation after the tubular body is in engagement with the saw, and means for automatically stopping the rotation of said carrier after it has made a complete revolution.
16. In a machine for sawing tubular bodies, a rotatable saw-carrier, and means for rotating the same, a saw-arbor journaled in said carrier at one side of the axis of the carrier, said arbor having a saw thereon, a feeding device having a series of holders thereon, each adapted to hold a tubular body, means for constantly rotating said saw, means for holding said carrier stationary, means for moving said feeding device intermittently to bring the holders successively into position opposite the end of the saw-carrier, with the tubular body in engagement with the saw, means for automatically starting said carrier into operation each time a tubular body is brought into engagement with the saw, and means for automatically stopping the rotation of the carrier after it has made a complete revolution.
17. In a machine for sawing tubular bodies, a rotatable saw-carrier and means for rotating the same, a saw-arbor journaled in said carrier at one side of the axis of the carrier, said arbor having a saw thereon, a feed-wheel having one or more holders thereon each adapted to hold a tubular body, means for constantly rotating said saw, means for holding said carrier stationary, means for moving said feed-wheel to bring a holder opposite the end of the saw-carrier, with the tubular body in engagement with the saw, means for automatically starting said carrier into operation after the tubular body is in engagement with the saw, and means for automatically stopping the rotation of said carrier after it has made a complete revolution.
18. In a machine for sawing tubular bodies, a rotatable saw-carrier, and means for rotating the same, a saw-arbor journaled in said carrier at one side of the axis of the carrier, said arbor having a saw thereon, a feed-wheel having a series of holders thereon, each adapted to hold a tubular body, means for constantly rotating said saw, means for holding said carrier stationary, means for moving said feed-wheel intermittently to bring the holders successively into position opposite the end of the saw-carrier, with the tubular body in engagement with the saw, means for automatically starting said carrier into operation each time a tubular body is brought into engagement with the saw, and means for automatically stopping the rotation of the carrier after it has made a complete revolution.
19. In a machine for sawing tubular bodies, a saw, means for rotating the same upon its axis, a feed-wheel having one or more holders thereon each adapted to hold a tubular

body transversely to the plane of the saw, means for rotating said feed-wheel to bring the tubular body into engagement with the saw, means for holding the feed-wheel stationary while the tubular body is in engagement with the saw, and means for giving the saw an orbital movement about the axis of the tubular body when the feed-wheel is at rest.

10 20. In a machine for sawing tubular bodies, a saw, means for rotating the same upon its axis, a feed-wheel having a series of holders thereon each adapted to hold a tubular body transversely to the plane of the saw, means for rotating said feed-wheel intermittently to bring the tubular body into engagement with the saw, means for holding the feed-wheel stationary each time a tubular body is brought into engagement with the saw, and 25 means for giving the saw an orbital movement each time the feed-wheel is stopped.

21. In a machine for sawing tubular bodies, a pair of saws arranged in parallel planes, means for rotating said saws about their axes, 25 a feed-wheel having one or more holders thereon, each adapted to hold a tubular body with its end portions projecting beyond the holder into the planes of the saws, means for rotating said feed-wheel to bring the tubular 30 body or bodies into contact with the saws, means for holding the feed-wheel stationary while a tubular body is in engagement with the saws, and means for giving said saws a simultaneous orbital movement about the 35 axis of the tubular body engaged by the saws while the feed-wheel is at rest.

22. In a machine for sawing tubular bodies, a saw, means for rotating the same upon its axis, a feeding device having a series of holders thereon each adapted to hold a tubular body transversely to the plane of the saw, means for rotating said feed-wheel intermittently to bring said tubular bodies successively into engagement with the saw, means 45 for holding the feed-wheel stationary while each tubular body is in engagement with the saw, and means for giving said saw an orbital movement while the feed-wheel is stationary.

23. In a machine for sawing tubular bodies, 50 a saw, means for operating the same to sever the tubular bodies, a feeding device having a series of holders thereon each adapted to hold a tubular body in the plane of the saw, means for intermittently operating said feeding device to bring successive holders opposite the saw, a cleaning device, and means for moving said cleaning device into and out of the interior of each holder after it has passed the saw and while the feeding device 55 is at rest.

24. In a machine for sawing tubular bodies, a pair of saws, means for operating the same to sever the tubular bodies, a feeding device having a series of holders thereon each 60 adapted to hold a tubular body with its ends

projecting beyond the end of the holder into the planes of the saws, means for intermittently operating said feeding device to bring successive holders opposite the saws, a cleaning device and means for moving said cleaning device into and out of the interior of each holder after it has passed the saws and while the feeding device is at rest. 70

25. In a machine for sawing tubular bodies, a pair of saws arranged in parallel planes, 75 a feed-wheel having a series of holders thereon each adapted to hold a tubular body with its end portions projecting transversely of the planes of the saws, means for intermittently moving said feed-wheel to bring successive holders between the saws, a longitudinally-movable shaft or spindle having a cleaning device thereon arranged in the rear of the saws, and means for giving said spindle a longitudinal reciprocating movement 80 each time the feed-wheel is stopped.

26. In a machine for sawing tubular bodies, a pair of saws and means for operating the same to cut said bodies transversely, a feed-wheel having a series of holders thereon, 90 each holder having a hinged outer jaw and being adapted to hold a tubular body with its ends projecting into the planes of the saws, means for rotating said feed-wheel intermittently, a curved guide extending 95 around the upper and rear portions of the feed-wheel and adapted to hold said hinged jaws closed while the tubular bodies are being cut off, a cleaning device at the rear of the saws, and means for moving said device 100 into and out of the holders while the jaws are closed by said guide and the feed-wheel is at rest.

27. In a machine for sawing tubular bodies, the combination with a pair of saws arranged in parallel planes, means for constantly rotating said saws about their axes, and means for giving said saws an intermittent orbital movement, of a feed-wheel having a series of holders thereon, mechanism 105 for intermittently operating said feed-wheel, and means for automatically throwing said feeding mechanism out of action after each movement of the feed-wheel.

28. In a machine for sawing tubular bodies, 110 the combination with a pair of saws arranged in parallel planes and means for constantly rotating said saws about their axes, of a feed-wheel, means for intermittently operating said feed-wheel, mechanism for giving said saws an intermittent orbital movement, and means for automatically throwing said mechanisms out of action after each movement of the feed-wheel.

29. In a machine for cutting off the heads 115 of sheet-metal cans, the combination with a pair of saws arranged in parallel planes and means for rotating said saws about their axes, of a holder arranged to hold a can-body with its end portions in engagement with the saws, 120

and means for giving said saws and holder a complete orbital movement relatively to one another during the engagement of the saws with the can-body, to cause the severance of the can-heads.

30. In a machine for sawing tubular bodies, the combination with a saw, and means for rotating said saw about its axis, of a holder arranged to hold a tubular body transversely to the plane of the saw and in engagement with the saw, and means for giving said saw and holder a complete orbital movement relatively to one another during the engagement of the saw with the tubular body, to cause the severance of the tubular body.

31. In a machine for sawing tubular bodies, the combination with a saw, and means for rotating said saw about its axis, of a feeding device having a holder thereon adapted to hold a tubular body transversely to the plane of the saw, means for moving said feeding device to bring said tubular body into engagement with the saw, means for automatically locking said feeding device in stationary position while the tubular body is engaged by the saw, and means for moving said holder and saw relatively to one another, while the feeding device is stationary, to cause the saw-teeth to cut circumferentially around the tubular body from the interior of the tubular body outwardly.

32. In a machine for cutting off the heads of sheet-metal cans, the combination with a pair of circular saws arranged in parallel planes, and means for rotating said saws about their axes, of a feeding device having a holder thereon, said holder being arranged in a plane between the saws and adapted to hold a can-body with its end portions projecting into the planes of the saws, means for moving said feeding device to bring the can-body into engagement with the saws, means for locking said feeding device in stationary position while the can-body is engaged by the saws, and means for moving said holder and saws relatively to one another while the feeding device is stationary, to cause the teeth of the saws to cut circumferentially around the can-body from the interior of the can-body outwardly.

33. In a machine for sawing tubular bodies, a circular saw and means for rotating the same about its axis, a holder adapted to hold a tubular body transversely to the plane of the saw, means for giving the saw and holder a relative feeding movement to cause the saw to make an initial cut through the wall of the tubular body at one side thereof, means for stopping this feeding movement after this initial cut has been made, and means for moving said saw and holder relatively to one another, after the feed movement has ceased, to cause the saw-teeth to cut circumferentially around the tubular body from the interior outwardly.

34. In a machine for cutting off the heads of sheet-metal cans, the combination with a pair of circular saws arranged in parallel planes and means for rotating said saws about their axes, of a holder arranged in a plane between said saws and adapted to hold a can-body with its end portions projecting into the planes of the saws, means for giving the saws and holder a relative feeding movement to cause the saws to make initial cuts through the wall of the can-body at one side thereof, means for stopping this feeding movement after the initial cuts have been made, and means for moving said pair of saws and the holder relatively to one another, after the feed movement has ceased, to cause the teeth of both saws to cut circumferentially around the can-body from the interior outwardly.

35. A machine to cut the heads and bottoms from can-bodies, having in combination a plurality of clamps to stationarily clamp can-bodies between their ends; means for intermittently moving said clamps to bring them successively to the operative position, and means to simultaneously make two cuts, one at each end, around the clamped can-body in position, whereby both ends of the can will be severed and removed while the body remains held in the clamp. 95

36. In a machine of the class described, the combination of a crank; a cutter-shaft carried by said crank; means for revolving said cutter-shaft continuously; means for revolving said crank intermittently, and a can-body clamp whose center is coincident with the axis of the cutter-shaft.

37. In a machine of the class described, the combination of a crank; a cutter-shaft carried by said crank and provided with a pinion; a shaft at the axis of said crank and carrying a gear which meshes with the pinion on said cutter-shaft to revolve the latter; means for revolving said gears and cutter-shaft continuously; means for revolving said crank intermittently and thereby move the revolving cutter-shaft in a circular path, and a can-body clamp whose center is coincident with the axis of the cutter-shaft. 105

38. In a machine of the class described, the combination of a stationary table; a bearing supported above said table; a revolute sleeve extending through said bearing and carrying a crank; means for revolving said sleeve; a cutter-shaft carried by said crank; a shaft extending through said sleeve; means for transmitting motion from said latter shaft to the cutter-shaft, and a can-body clamp whose center is coincident with the axis of the cutter-shaft. 115

39. In a machine of the class described, the combination of a crank; a cutter-shaft carried by said crank; means for revolving said cutter-shaft; means for revolving said crank intermittently whereby to move the 130

cutter-shaft in a circular path; a plurality of can-body clamps; and means for successively moving said clamps into operative position with respect to said cutter-shaft.

5 40. In a machine of the class described, the combination of a crank; a cutter-shaft carried by said crank; means for revolving said crank to move the cutter-shaft in a circular path; a revoluble head carrying a plurality of can-body clamps, and means for intermittently revolving said head to successively bring the clamps into position opposite the crank-axis and hold them at rest while the cutter-shaft is moved in a circular path.

5 41. In a machine for cutting can-bodies, the combination of two cranks confronting

each other but spaced apart; a rotary cutter carried by each crank; a plurality of movable clamps each adapted to clamp a can-body 20 between its ends; means for successively moving the said clamps to a position in the space between the said two cranks with their centers coincident with the axis of the cutter-shaft, and means for intermittently revolving both cranks to cause the cutters to sever and remove the head and bottom while the body remains held in the clamp. 25

In testimony whereof I affix my signature in presence of two witnesses.

EUGENE J. LOGAN.
